PAD FOR RING BOXES

William Jefferson, Chicago, Ill., assignor to F. H. Noble & Co., Chicago, Ill., a corporation of Illinois

Application April 17, 1939, Serial No. 268,257

3 Claims. (Cl. 206—76)

The present invention relates to the pad member of small ornamental boxes used for the display and preservation of finger rings, especially those having sets, such for instance as the boxes 5 described in Shields Patent No. 1,906,822. The container itself may therefore be understood to be a small ornamental box having its body member formed to receive the pad to which my invention alone relates.

10 The object of my invention is the provision of a durable pad which will at any time receive rings varying widely in size, and not be weakened or broken down by their use with large wide rings so as to be thereafter ineffective for use with thin, 15 narrow rings. A further object is to provide a pad with a ring slot which will throughout its life hold a ring therein firmly at the angle determined by its construction, without liability of variation due to its impairment by previous use. 20 With the foregoing objects and incidental constructional advantages in view, I have devised and invented the novel pad for finger ring boxes hereinafter described in detail and illustrated in the accompanying drawing, the essential elements of my invention being recited in the appended claims.

In the drawing, Figure 1 is a perspective view of my novel pad;

Fig. 2 is a longitudinal vertical section of the 30 pad;

Fig. 3 is a perspective view of the two cover members employed in the construction of my pad, shown as separated, unfolded blanks; and

Fig. 4 is a similar perspective of a formed sheet 35 metal member used as the body or frame of the pad.

Like reference characters indicate like parts in all the figures of the drawing.

The sheet metal frame of my pad (see Fig. 4) 40 is a shell of the general rounded contour of the finished pad, formed with a skirt portion 1, merging into upper top section separated along cut lines, and comprising a rear section 2, curved at the rear to accommodate the usual spring 45 hinge of the ring box, and forward top sections cut and bent to provide a central tongue section 3 formed with inclined flanges 4 and 5 on each side. The top section 3a at the base of the tongue extends in the same plane as the rear portion 2 of the frame and forward section of the top on each side of and forwardly of the base of the tongue, while the section 3b at the free end of the tongue is bent along a transverse line to form an inclined wall extending downwardly and rearwardly at the angle at which it is desired the ring

55 shall stand in the pad. It will be noted that the cuts defining the section 3a of the tongue are inclined so that the base is narrower than the front and the tongue is thereby rendered more freely resilient. The flanges 4 and 5 on the opposite sides of the tongue serve to stiffen it somewhat so its resiliency is manifested principally across its base.

Adjacent the opposite ends of the gap between the sections 2 and 3 of the frame, the metal at the 10 top of the skirt portion 1 is rolled down inwardly at each side, to form rounded edges over which the covering materials can be applied smoothly.

These covering materials include a rectangular piece of thin cotton batting 6 or other similar 15 spongy substance of substantially the same width as the upper faces of the pad and of such length as to provide for folding the batting down into the gap between the tongue 3 and the forward edge of the rear portion 2 of the frame in forming a ring pocket of the shape shown in Fig. 2.

The finishing fabric which covers the completed pad is formed from a blank 7 of the shape shown in Fig. 3. The end sections, marked respectively 8 and 9, are drawn down around the 25 skirt of the frame on opposite sides of the ring opening, while the narrower central section 10 is drawn downwardly with the cotton batting beneath it into the gap between the tongue 3 and the forward edge of the rear portion 2 of the 30 frame to form the ring pocket.

It may here be explained that in manufacturing the pad the sheet metal of which the frame is made is coated with a cementing material of such character as to soften and become adhesive 35 when heated. This coated material is run through blanking and forming mechanism to produce the frame members described. These frame members and the associated covering materials are then subjected to the action of a covering die apparatus which acts to first form the ring pockets by drawing down the central portions of the materials into the recess between the parts 2 and 3 of the frame, and then successively folds the materials on opposite sides of the pocket 40 down to the bottom of the skirt of the frame and then upwardly on the inside of the skirt by electrically heated die members which cement the covering material to the frame to form the completed pads.

50 I claim:

1. A finger ring pad comprising a sheet metal frame member formed with a skirt portion and top sections integrally connected therewith including a rear top section and a yielding tongue 55

section extending from front to rear and terminating in an inclined wall section spaced forwardly of said rear top section, and padding material secured to said skirt portion and top sections and extending downwardly in a loop between said rear top section and inclined wall section of the tongue to form a ring pocket.

5. A finger ring pad according to claim 1 in

which the base of the tongue is narrower than the inclined wall section.

3. A finger ring pad according to claim 1 in which the base of the tongue is narrower than the inclined wall section, and the sides of the 5 tongue are provided with stiffening flanges.

WILLIAM JEFFERSON.
